CLAIM

The ornamental design for a head massager as shown and described.

DESCRIPTION

FIG. 1 is a perspective view of a head massager showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, shown in an open state; and,

FIG. 9 is another perspective view thereof, shown in another open state.

The broken lines in the drawings depict portions of the head massager that form no part of the claimed design.
